United States Patent

Des. 239,974
Patented May 18, 1976

239,974

STRINGED MUSICAL INSTRUMENT

Walter J. Pelensky, 19C Manheim Gardens,
Philadelphia, Pa. 19144

Continuation of design application Ser. No. 256,206, May
23, 1972. This application Nov. 25, 1974, Ser. No.
527,131

Term of patent 14 years

Int. Cl. D17—03

U.S. Cl. D56—1 A

Fig. 2

Fig. 1

Fig. 3

FIG. 1 is a front elevational view of a stringed musical instrument, specifically a Ukrainian bandurka, showing my new design;

FIG. 2 is a left side elevational view with the strings omitted for convenience of illustration; and

FIG. 3 is a right side elevational view thereof.

This application is a continuation of design application Ser. No. 256,206, May 23, 1972.

I claim:

The ornamental design for a stringed musical instrument, as shown and described.
